(57) **CLAIM**

The ornamental design for an elevated pontoon platform with curved steps, as shown and described.

DESCRIPTION

FIG. 1 is a perspective view of the elevated pontoon platform with curved steps showing the design.

FIG. 2 is a top view thereof.

FIG. 3 is a bottom view thereof.

FIG. 4 is a front view thereof.

FIG. 5 is a rear view thereof.

FIG. 6 is a side view thereof; and,

FIG. 7 is an environmental side view.

The portions of the disclosure shown in broken lines form no part of the claimed design.
